INGOT STOOL

Howard Felsing, Wheeling, W. Va.

Application July 1, 1936, Serial No. 88,324

5 Claims. (Cl. 22—139)

This invention relates to a base for ingot molds, and more particularly to a base or "stool" on which the ingot mold may be supported during pouring of the molten steel thereinto and during cooling of the poured metal.

As is well known in the art, molds for forming steel ingots preparatory to reducing the steel to sheets, plates, and the like, consist of four vertical defining walls devoid of opposite ends, the mold ordinarily being of elongated frusto-pyramidal shape. The mold during pouring of the molten steel is supported in upright position on a solid slab of metal, the slab, although of greater area than the area of the mold, forming a bottom for the latter. Slabs, or "stools", as they are termed in the art, of the character referred to, quickly become useless after a comparatively short period of service for the reason that the molten steel through repeated impingement thereon and contact therewith erodes and rapidly disintegrates the metal of the slab. Moreover, the slabs are easily broken through rough treatment accorded them in the mill.

One of the objects of my invention is to provide a stool for supporting ingot molds having a steel outer reinforcement frame or casing and an interior cast iron floor or face, the steel casing being designed to absorb shocks during rough treatment so as to render the iron floor unharmed during such abuse. Cast iron, preferably, gray iron, is preferably used for the ingot-contacting face because it has properties tending to discourage the adherence thereto of the molten steel contained within the mold.

Another object of the invention is to provide a stool of the character mentioned in which a portion of the ingot contacting floor is readily renewable when worn, thereby eliminating the necessity for scrapping the entire stool, as is now the universal practice.

With these and other objects in view, the invention resides in the features of construction, arrangement of parts, and combinations of elements which will hereinafter be fully described, reference being had to the accompanying drawings, in which—

Figure 1 is a top plan view of the invention;

Figure 2 is a top plan view of the steel frame with the iron floor removed;

Figure 3 is a vertical sectional view taken on line 3—3, Fig. 1;

Figure 4 is a vertical sectional view taken on line 4—4, Fig. 1;

Figure 5 is an end elevational view of the central removable insert or shoe;

Figure 6 is a vertical sectional view taken on line 6—6, Fig. 5;

Figure 7 is an end elevational view of one of the removable end inserts or shoes; and

Figure 8 is a side elevational view of the same. 5

Referring to said drawings, the reference numerals 2 and 3 designate, respectively, the side and end defining walls of a rectangular frame, preferably made of steel, the same having an integral bottom 5 and a rectangular annular seating flange 6 depending from said bottom. 10

Rectangular apertures 7 are provided in the bottom 5 at a spaced distance from the four right angle corners of the frame, the defining side walls of the apertures being divergently inclined downwardly. Said apertures 7 are defined at their upper ends by annular upstanding flanges 8 formed integral with the bottom 5. 15

The central area of the bottom 5 is somewhat thicker than the remaining area thereof and this heavier central portion has formed therein laterally extending rectangularly shaped apertures 9 whose side walls are also divergently inclined downwardly. The upper surface of the heavier or thicker area of the bottom at either side and 20 intermediate the apertures 8 is formed with a plurality of laterally extending furrows 10 curved in cross section, as shown in Figs. 2 and 3.

The steel frame, above described in detail, is designed to serve as a casing or reinforcement 30 for an interior cast iron floor, the two elements together comprising the ingot stool. The cast iron, preferably gray iron, is cast in its molten state into the frame by any of several methods well known in foundry practice and to those 35 skilled in the art.

The iron floor 11 occupies a level above the plane of the sides 2 and ends 3 of the steel frame and preferably had its entire perimeter chamfered, as shown at 12. It will also be noted that the inclined sides of each of the apertures 7 and 9 tend to key the iron in place within the steel reinforcing frame. Moreover, the side and end walls 2 and 3 of the frame are undercut at the four corners, as shown at 13, to more effectively 45 key the iron to the steel frame. Additionally, if desired, a plurality of integral dove-tail lugs 15 may protrude inwardly from the steel frame to be embedded within the iron for the same purpose. 50

The central area of the iron floor is appropriately cored during molding so as to form a central recess or depression of predetermined area and depth in the casting, the bottom of the cavity being provided with undulations 16 (Fig. 3), and 55

the opposite vertical end walls defining the cavity being convergently inclined downwardly.

- The central recess in the iron floor is designed to removably receive therein a set of inserts or 5 shoes consisting of end shoes 17 and an intermediate shoe 18. Each of the end shoes 17 is identical and is of trapezoidal shape in cross section, while the intermediate shoe 18 is so shaped in cross section that it serves as a wedge 10 or key plate to effectively lock each of the shoes in interfitting relation snugly within the registering recess. As shown in Fig. 3, the shoes, when positioned, present a flat plane surface continuation of the face of the iron floor 10. 15 Tie rods 20 extend transversely of the stool passing through the side walls 2 of the frame; the floor 10; spaced upstanding bearings 21 formed integral with the bottom 5, and through registering cored passages 22 formed in the inserts 17 and 18. Nuts 22 threadedly received by the opposite ends of each tie rod are protected by and housed within encircling guards 23 formed integral with the side walls 2 exteriorly thereof. 20 An eye bolt 24 engages the center tie rod midway between its ends and depends downwardly through the stool through an aperture 27 to receive a nut 25, the insert 18 being suitably cored, as shown at 26, to receive the eye of the bolt. Manifestly, so constructed, the removable shoes 17 and 18 cannot be disturbed without first freeing the eye bolt 24.

Bosses 28 protrude upwardly from the stool at the four corners thereof to provide limit 30 stops to prevent chance shifting of the ingot mold 29 from the stool while the same is being transported on a wheeled vehicle or buggy.

In practice, the ingot mold 29 is placed upon the stool in an upright vertical position so that the opening in the bottom of the mold will register with the removable cast iron shoes 17 and 18. As the molten steel is poured into the mold it will impinge against the iron shoes, but will not tenaciously cling thereto because of certain 40 properties contained in gray iron tending to discourage the cohesion with the steel. Thus, the poured ingot and its mold may readily be removed from the stool following a reduction in the temperature of the steel.

Following a period of use the floor of the stool will naturally become eroded and crystallized rendering the same unfit for further service. In order to remedy the defect, all that need be done is to replace the worn shoes with new inserts which may be accomplished in a readily obvious manner. After a considerable period of use it may be found necessary to replace the entire stool, but such will not be required until several sets of inserts have been worn and replaced inasmuch as the molten steel as it is 50 poured into the mold will impinge upon said inserts, thus, consequently, placing upon these elements the maximum use, wear and abuse.

While gray iron affords a comparatively inexpensive floor for the stool, it is, as is well known in the art, exceedingly brittle and will not withstand hard shocks and jars to which an ingot

stool is subjected in a steel mill. It is for this reason that the cast iron floor is reinforced with a frame of steel—a metal much harder and better adapted to withstand hard usage and abuse.

Moreover, while I have herein described the floor as consisting of gray iron, it will be understood that other metals, as copper, having a tendency to discourage the adherence of steel thereto may be substituted therefor. However, 10 cast iron is preferred because it is one of the most inexpensive metals adapted for the particular purpose.

Although I have illustrated and described a preferred embodiment of the invention, it will 15 be apparent that various changes and alterations might be made in the general form and arrangement of parts described without departing from the invention. Hence, it is not intended to be limited to the precise details set 20 forth, and I shall consider myself at liberty to make such changes and alterations as fairly fall within the spirit and scope of the appended claims.

What is claimed is:

1. An ingot stool consisting of a cast gray iron ingot supporting floor having its perimeter encase within and reinforced by a base of steel, a depression formed in an area of said floor, and a removable section received by said depression occupying substantially the same plane as that occupied by the ingot supporting floor.

2. An ingot stool consisting of a metal supporting floor having its perimeter encased within and reinforced by a metal base, a depression formed in an area of said floor, and a plurality of interfitting shoe elements receivable in said depression, one of said shoe elements serving as a key wedge to maintain said shoe elements in interfitting relation.

3. An ingot stool consisting of a steel reinforcing frame adapted to receive therein a quantity of cast iron in its molten state which, when solidified, is designed to serve as an ingot supporting floor, a recess formed in an area of said floor, and a removable section adapted to be received within said recess.

4. An ingot stool consisting of a steel reinforcing frame adapted to receive therein a quantity of cast iron in its molten state which, when solidified, is designed to serve as an ingot supporting floor, integral lugs formed on said frame adapted to become embedded within the metal of said floor, a recess formed in an area of said floor, and a removable section adapted to be received within said recess.

5. An ingot stool including a steel reinforcing frame forming a mold, a floor formed of cast iron in its molten state which when poured into the frame and solidified has interlocking engagement with the frame, said floor having a recess formed in an area thereof, and a plurality of interfitting shoe elements receivable in said recess, one of said shoe elements serving as a key wedge to maintain said shoe elements in interfitting relation.

HOWARD FELSING.
